UNITED STATES PATENT OFFICE.

JAMES D. GARVEY, OF CHICAGO, ILLINOIS.

FOUNTAIN BRUSH.

Application filed January 15, 1921. Serial No. 437,524.

To all whom it may concern:

Be it known that I, JAMES D. GARVEY, a citizen of the United States, and a resident of Chicago, in the county of Cook and State 5 of Illinois, have invented certain new and useful Improvements in Fountain Brushes, of which the following is a description, reference being had to the accompanying drawing, which forms a part of my specification.

10 My invention relates to improvements in fountain brushes wherein the reservoir or container may be located at a distance from the brush proper; the container being intended to be suspended or arranged in a 15 plane above the point where the brush or brushes are intended to be employed.

My invention has for its object the provision of a construction whereby a plurality of brushes may be simultaneously and yet 20 independently supplied with the liquid in the container; each brush supply being separately controllable, at the will of the operator, at a distance removed from the container or receptacle portion of the device.

A further object of my invention is to provide a simple and easily operable construction more especially adapted for use as a paint, varnish or staining brush, either in 30 a factory or building interior or for use on scaffolds, ladders and the like; the invention possessing advantages which will be readily apparent from the detailed description of the accompanying drawing, 35 wherein:—

Figure 1 is a perspective view of the receptacle portion of my improved fountain brush.

Figure 2 is a vertical sectional view thereof with a brush secured thereto.

Figure 3 is a detail sectional plan view, taken on the line 3—3 of Figure 2 looking in the direction of the arrows.

Figure 4 is a detail view in perspective 45 taken substantially on a portion of the line 3—3 of Figure 2; the walls of the reservoir being broken away.

Figure 5 is a detail view in perspective of the pull chain roller and guide.

50 My invention, as previously stated, relates to a fountain brush, more especially for painting, varnishing and the like, to be suspended or supported at an elevation and contemplates a construction adapted for use 55 by a number of operators that may be painting or varnishing at slight distances re-

moved from each other, but all securing their supply of paint, varnish and the like from a single container which consists of a suitable sized receptacle preferably provided 60 with cylindrical side walls, as shown at 10. The container is also preferably provided with a dished bottom as at 11 so as to cause the paint, varnish and the like to readily flow toward the central portion of the bottom 65 and therefore not become lodged at the point of juncture between the side walls and bottom. In the particular exemplification of the invention, the bottom is substantially saucer-shape and arranged to overlap the 70 outer sides of the side wall 10, to which it is secured in any suitable manner, as for example by soldering or otherwise to provide a fluid-tight joint. The flat or intermediate portion of the bottom is provided 75 with a plurality of openings, for example three in number in the drawings, each of which is shown provided with a flanged nipple as at 12. The nipples are preferably disposed through the openings so as to have 80 the flanges 13 extend flush with the bottom to which the flanges are soldered or otherwise secured to provide fluid-tight connections. The apertures or openings in the nipples are flared at the upper or inner ends 85 thereof to provide suitable valve-seats as at 14, see Figure 2, adapted to receive the spring-controlled frusto-conical valves or stoppers 15 which are secured to the lower end of rods 16. The rods 16 are preferably 90 of length to extend to a point in proximity to the top or lid-portion 17 of the receptacle or container 10.

The interior of the container 10, at a point somewhat above the bottom thereof, 95 is provided with a diametrically disposed strip 18, the ends whereof are shown secured or held in place by means of angle members or brackets 19, 19 which latter are soldered or otherwise suitably secured to the 100 wall 10 so as to have one portion or leg of each angle disposed in a direction transversely of the container-interior and at diametrically opposite points. The ends of the strips 18 are shown secured to the inwardly disposed legs or portions of the angle members 19 by means of suitable U-shaped clips or members 20, see Figures 2 and 4, which are adapted to embrace the ends of the strip member 18 as well as the 110 free portion or leg of the members 19 and these clips or members 20 are in turn re-

movably held in place in any suitable manner, as for example by cotter-pins 21. The strip 18, at points coincident with the valve-operating rods 16, are provided with apertures for the passage of said rods. The strip not only acts as a guide for the valve-stems but also intends to maintain springs 22, disposed about the valve-stems, under compression during the operation of the valves; it being understood that a spring 22 is disposed about the stem or rod 16 of each valve as clearly shown in Figure 2; while the lower end of each spring bears down on the top surface of its respective valve 15. As is clearly apparent from this construction, the valves may be moved upwardly from their seats through an upward pull on the rods or stems 16, thereby placing the springs under compression whereby the valves are returned to their seats when the stems are relieved of the upward pull; the valves being maintained on their seats by the constant pressure exerted by the springs.

In addition to serving as a guide for the valve-stems and to maintain the springs under pressure, the member or strip 18 also provides means for securing and maintaining cylindrical screens 23 in place. These screens 23 are secured to the strip or member 18 and held on the bottom 11 of the container in any suitable manner; the screens 23 being of an internal diameter somewhat larger than the external diameter of the valves 15 so as to permit free movement or operation of the valves to and from their seats. The screens prevent foreign matter or heavy sediment from becoming lodged about the valve-seats where it would interfere with a proper seating of the valves as well as possibly clog the conduits or tubes 24 which extend from the members 12 to the different hand brushes, one of which is shown at 25 in Figure 2. The conduits 24 are intended to be flexible and preferably consist of rubber tubing, with one end suitably attached to the members 12, as illustrated for example in Figure 2, where the member 12, at the left hand side of the figure, is shown provided with the tube 24.

The handle of the brush 25 is provided with a suitable duct disposed longitudinally therethrough and terminating at the base portion of the bristles of the brush. The duct in the handle portion may be provided with a short metallic tube adapted to extend beyond the outer end of the handle to receive the end of the tube 24. The container 10 is provided with a suitable bail as at 26.

As is evident from the construction shown in Figure 2, ready access to any or all of the valves in the container may be had and if necessary any or all of the valves and springs easily removed for repair or replacement by simply removing the cotter-pins 20 whereby the clips 20 and the member or

strip 18 are secured to the angle members 19. The removal of the cotter-pins will enable the strip 18 with the valves and valve-stems, as well as the strainer members 23, to be taken out through the top of the container.

The lid or cover 17, like the bottom 11, is preferably somewhat saucer shaped, with the curved sides arranged to fit over the outside of the container, as shown in Figure 2. In the construction shown, the lid or cover 17 is preferably held in place by means of a suitable cord or wire 27 which is adapted to be laced or passed about projections or buttons secured to the sides of the cover or lid 17 and to the sides of the container 10 at suitable points and in staggered relation, as shown in Figure 1, when the cover or lid 17 is in proper position on the container or receptacle. The cord or wire 27 may have one end secured to one of the projections or buttons either on the container or cover, and then passed in the zig-zag manner shown in Figure 1; for example, we will assume that one end of the cord or wire 27 is secured to the projection 28 secured to the cover or lid 17, in which instance the wire or cord will then be passed about a projection 29 on the container and thence upwardly about a second projection 28 on the cover or lid and down about a second projection 29 on the container and so on until the wire or cord has passed about the container in the zig-zag or laced manner, whereby the lid or cover will not only be firmly held in place, but may be easily and entirely removed.

At points coincident with the valve-stems 16, the cover or lid 17 is provided with suitable openings for the passage of the flexible elements or chains 30 which are secured to the upper ends of the valve-stems 16. The cover or lid 17, at a point in proximity to each opening therein, is provided with the U-shape brackets 31 and shown in detail in Figure 5. The lower ends of the sides of the brackets 31 are disposed at right angles to the main portion so as to extend parallel with the lid or cover 17 to be riveted or otherwise secured thereto. The brackets 31 are each provided with a roller 32; the rollers 32 being rotatably arranged in the brackets 31 so as to have the perimeters thereof disposed in proximity to the vertical planes of the valve-rods and therefore also to the openings in the lid or cover 17, in order that the flexible elements or chains 30 may pass over the rollers 32 and transmit a straight upward pull on the valve-stems 16. The sides of the container 10, adjacent to the cover 17 at points coincident with the direction in which the respective pull chains 30 are disposed, is provided with brackets 33 which may be similar to brackets 31 and these brackets 33 are each provided with a

roller 34 over which the respective chains pass and are kept out of frictional contact with the edges of the cover 17. The chains may be of any desired length to permit operation of the valves at a considerable distance removed from the container 10 commensurate with the length of the flexible conduits or tubes 24.

In the particular exemplification of the invention as disclosed in Figure 1, where the fountain brush is provided with three outlets or valves, the pulley brackets 31 are secured to the cover or lid so as to have two of the brackets disposed in opposite directions at diametrically opposite points, while the third is arranged at a point intermediate of the two mentioned brackets and disposed in a direction substantially at right angles to the two first mentioned brackets, thus leaving one side of the pail or container free to contact with a side wall when suspended thereagainst. The brackets 33 are therefore also secured to different sides of the container so as to be in line with the pull chains or cords 30, the ends whereof may be provided with rings or handles if desired.

In order that the container may be properly supported when not suspended by its bail, I show the container provided with supports or legs 35 which are disposed in the sloping manner shown so as to prevent the container from being readily tipped over. The supports or legs 35 may be of the type shown and described in my copending application, or of any suitable construction consistent with lightness.

With my improved construction, as illustrated in the drawing, it is apparent that at least three operators may simultaneously use the fountain brush and each operator may be at a distance removed from the container or receptacle portion of the brush as well as from each other, as their supplies are independently controllable by the valve mechanism which controls the flow to the brush proper of the respective operators; the manipulation of the brush proper by an operator being permissible without in any way interfering with the operation of the other operator or operators. The pulley arrangement shown and described will at all times induce a positive upward pull to be exerted on the valve-stems for the purpose of opening the valves 15. The container or receptacle 10, in practice, is filled and suspended or supported above the point of application of the paint, varnish, stain or the like, so as to induce a flow by gravity of the paint or other contents through the tubes or conduits 24 when the valves 15 have been operated or removed from their seats by a pull exerted on the chains or flexible elements 30. In the event that the bristles of the brush proper fill with paint, varnish or the like, faster than it can be applied by the manipulator,

the flow into the conduits or tubes 24 may be quickly shut off by releasing the pull-chains or cords 30 which allow the springs 22 to force their respective valves to their seats; the amount of flow through the valves being 70 also readily controlled by the degree of movement of the valve so that the flow of the paint, varnish and the like into the brush proper is at all times under the control of the operator; with each operator absolutely 75 independent of the other.

It is evident that the number of conduits and hand brushes may be varied to suit the size or capacity of the container or receptacle of the fountain brush, and that other 80 modifications may be made without departing from the spirit of my invention which has been disclosed in what I believe at present to be its best form, but I do not wish to be understood as limiting myself to the exact 85 construction shown and described.

What I claim is:—

1. A device of the character described, comprising a receptacle or container, the bottom whereof is provided with a plurality 90 of openings terminating in outwardly disposed extensions, a spring-controlled valve disposed on each outlet within the container, a guide member disposed transversely of the container and apertured for the passage 95 of the valve-stems, said guide member being removably secured within the container and adapted to place the valve springs under compression, a cover or lid for the container provided with openings adapted to be in vertical alignment with the valve-stems, guide pulleys secured on the cover or lid at points coincident with said openings, and pull-cords or flexible elements secured to the valve-stems and disposed through the openings in the cover or lid and about the pulleys adjacent to the respective openings. 100

2. In a device of the character described, a container, the bottom whereof is provided with a plurality of openings, apertured extensions secured in said openings, the inner ends of the apertures in the extensions being flared to provide valve-seats, a cone-shaped valve for each opening, said valves being provided with elongated stems disposed upwardly in the container, a guide member or strip disposed transversely within the container, means whereby said guide member or strip is removably secured in place, a compression spring disposed about each valve-stem intermediate of the valves and said guide member or strip, a screen disposed intermediate of the guide member or strip and the bottom of the container and encircling each outlet opening so as to permit the 115 valve to reciprocate freely therein, a removable cover or lid for the container provided with a plurality of openings corresponding with the openings in the container bottom, pulleys or rollers rotatably mounted on the 120 130

1. container and lid at predetermined points, with those on the lid disposed adjacent to each opening therein, and a pull-chain or cord secured to each valve-stem, with each 5 cord disposed about a roller on the lid and a roller on the container, the rollers on the lid being disposed in different directions toward opposite sides of the container.
2. 3. In a device of the character described, 10 a container provided with a removable top, while the bottom is dished and provided with a plurality of extended outlets, a spring-controlled valve within the container for each outlet movable in the direction of 15 flow through said outlets, each valve being provided with an elongated stem disposed vertically within the container, means disposed transversely within the container at a distance removed from the bottom and re- 20 movably secured to the side walls of the container, said means being adapted to act as a guide for the valve-stems, the container-top being apertured at points adapted to register with the valve-stems, guide rollers 25 mounted on said top at points coincident with the apertures therein, and flexible means secured to the valve-stems and disposed through the apertures in the container top and about said rollers.
3. 4. A device of the character described, comprising a container provided with a removable top, while the bottom is provided with a plurality of apertured bosses, a spring-controlled valve for the aperture in 35 each boss and closable in the direction of flow therethrough, each valve being provided with an elongated stem disposed vertically within the container to a point in proximity to the top thereof, a metallic strip 40 disposed transversely within the container at a point removed from the bottom thereof, means whereby said strip is removably secured to the side walls of the container, said strip being formed for the passage of the 45 valve-stems therethrough, the container-top being apertured at points adapted to register with the valve-stems, rollers rotatably mounted on the container-top at points coincident with the apertures therein, and flexible 50 means secured to each valve-stem and disposed about the rollers coincident with the respective apertures in said top.
5. A device of the character described, comprising a container provided with a re- 55 movable top, while the bottom is provided with apertured bosses disposed therebeneath and constituting outlets for the container, a valve for each outlet, closable in the direction of flow therethrough, each valve being 60 provided with an elongated stem disposed vertically within the container to a point in proximity to the top thereof, a metallic strip apertured for the passage of the valve- 65 stems therethrough, means whereby said metallic strip is removably secured to the side walls of the container, a spring disposed about each valve-stem intermediate of said strip and the valve whereby the latter is forced to its seat, foraminated means disposed intermediate of said strip and the container-bottom and about each valve so as to 70 permit reciprocatory movement of the valves therein, the container-top being provided with apertures at points adapted to register with the valve-stems, roller-holding 75 brackets secured on the container-top at points coincident with the apertures therein, with each bracket disposed toward a different side of the container, and flexible means secured to each valve-stem and disposed through its respective bracket and about the rollers thereof.
6. A device of the character described, comprising a container having a removable top, while the bottom is provided with a 80 plurality of apertured bosses formed to provide valve-seats within the container, a valve for each valve-seat seating in the direction of flow from the container, each valve being provided with an elongated stem disposed vertically within the container, a member disposed transversely of the container at a distance removed from the bottom thereof, means whereby said member is 85 removably secured to the container side walls, said member being apertured for the passage of the valve-stems therethrough, a spring disposed about each valve-stem intermediate of said member and the valve whereby the latter is normally forced to its 90 seat, a foraminated cage disposed intermediate of said member and the container bottom within which the valves are adapted to move, the container-top being provided with apertures at points adapted to 95 register with the valve-stems, roller-holding brackets mounted on the container-top at points adjacent to the apertures therein, roller-holding brackets secured adjacent to the top of the container on different sides 100 and at points coincident with the rollers on the top, and flexible means secured to each valve-stem and disposed over and beneath the rollers on the top and on the container.
7. A device of the character described, comprising a container, the bottom whereof is provided with a plurality of outlets, a valve for each outlet seatable in the direction of flow through the outlets, each valve being 105 provided with an elongated stem disposed upwardly within the container, a member disposed transversely of the container at a point removed from the bottom thereof and apertured for the passage of 110 said valve-stems to act as a guide therefor, means whereby said member is removably secured to the side walls of the container, a removable top for the container provided with apertures at points coincident with the 115

valve-stems, a bracket secured on the top adjacent to each aperture, with each bracket disposed toward a different side of the container, each bracket being provided with a 5 roller, roller-holding brackets secured to the sides of the container adjacent to the top and at points coincident with the brackets on the top, a flexible member secured to each valve-stem and disposed over and beneath the rollers in the respective brackets 10 on the top and on the container, each valve-stem being provided with a coil-spring disposed intermediate of the valve and said first mentioned member, and a foraminated 15 cage intermediate of said first mentioned member and the container-bottom and disposed about each valve to permit reciprocatory movement of the latter therein.

8. A device of the character described, 20 comprising a container having a dished bottom provided with a plurality of openings therein, each opening being formed to provide a valve-seat, a valve for each opening, each valve being provided with an elongated stem disposed upwardly within the 25 container, a guide strip disposed transversely of the container at a point removed from the bottom thereof, said guide strip being apertured for the passage of the 30 valve-stems therethrough, means whereby the strip is removably secured to the side walls of the container, a spring disposed about each valve-stem intermediate of the valves and said guide strip for normally 35 holding the valves on their seats, a dished top removably secured to the container and apertured at points coincident with the valve-stems, open ended brackets secured on the container-top at points coincident with

the apertures therein, with each bracket 40 provided with a roller and disposed toward a different side of the container, roller-holding brackets secured to the sides of the container adjacent to the top and at points coincident with the directions in which the 45 rollers on the top are disposed, and flexible means secured to each valve-stem and disposed about the rollers in said brackets on the top and on the container-sides.

9. A device of the character described, 50 comprising a container, the bottom whereof is provided with a plurality of outlets formed to provide valve-seats, a valve for each outlet, each valve being provided with an elongated stem disposed vertically within the container, an unattached cover or top for the container apertured at points coincident with the valve-stems, anti-friction means secured on the container-sides and on the top at points coincident with the 55 apertures therein, flexible means secured to each valve-stem and disposed about said anti-friction means, the anti-friction means for the respective valve-stems being disposed toward different sides of the container, 60 the sides of the container and said top being provided with projections or buttons at predetermined points, with the buttons on the top adapted to be in staggered relation with those on the container, and flexible means adapted to be laced about the 65 buttons of the container and top whereby the latter is removably secured in place. 70
